[57] **CLAIM**

An ornamental design for a baby bottle warmer with integral night-light, as shown and described.

DESCRIPTION

FIG. 1 is a top, right side isometric view of the baby bottle warmer with integral night light showing my new design. the broken line showing of a baby bottle is for illustrative purposes only and forms no part of the claimed design; and, FIG. 2 is an isometric view on a reduced scale. The left and rear views substantially identical to the views shown, the bottom view is flat and unornamented.

The isometric views of FIG. 1 and FIG. 2 illustrate the top, left front and right front views. The left and right rear views are identical to the right front view. The bottom is plain and, therefore, not illustrated.
